UNITED STATES PATENT OFFICE.

WALTER ALTHOFF, OF GENEVA, NEW YORK.

RAZOR-STROPPING DEVICE.

Application filed November 4, 1921. Serial No. 512,812.

To all whom it may concern:

Be it known that I, WALTER ALTHOFF, of Geneva, in the county of Ontario, in the State of New York, have invented new and useful Improvements in a Razor-Stropping Device, of which the following, taken in connection with the accompanying drawings, is a full, clear, and exact description.

This invention relates to a razor stropping device involving the use of a hollow handle or case containing an oscillatory blade-holder and a strop having portions thereof movable in opposite directions at opposite sides of the holder and adapted to be operated by hand against the action of a retracting spring together with means for transmitting motion from the strop to the blade-holder.

The main object is to enable the case to be held in one hand, while the strop is being operated by the other hand into and out of contact with opposite sides of the razor for sharpening purposes without liability of cutting said strop.

Another object is to provide means controlled by the strop for restoring the blade-holder to a neutral position in registration with an opening in one end of the case to facilitate the entrance and removal of the blade into and from the holder.

A further object is to provide a resilient back-rest for the blade to steady it in the holder during the stropping operation.

A still further object is to provide means for limiting the arc of oscillation of the blade-holder independently of the endwise movement of the strop or rather to permit a greater or less amount of endwise movement of the strop without oscillating the blade-holder beyond certain limits.

Other objects and uses relating to specific parts of the device will be brought out in the following description:

In the drawings:

Fig. 1 is a perspective view of a razor stropping device embodying the various features of my invention.

Fig. 2 is a longitudinal vertical sectional view of the same device taken on line 2—2, Fig. 1.

Figs. 3 and 4 are transverse sectional views taken, respectively, in the planes of lines 3—3 and 4—4, Fig. 2.

Figs. 5 and 6 are detail sectional views taken, respectively, in the planes of line 5—5, Fig. 6 and line 6—6, Fig. 2.

The razor stropping device, illustrated,

comprises a case —1— having rounded bottom and top walls —2— and —3— and substantially flat and parallel end walls —4—, the lower portion of one side and adjacent portion of the bottom being provided with a lengthwise slot or opening —5— for receiving and permitting the movement of a strop —6—, one of the end walls —4— being provided intermediate its lower and upper edges with an opening —7— through which the razor blade as —a— may be inserted and withdrawn into and out of a suitable holder —8—.

For convenience of assembling the various parts of the device within the case —1—, the latter is divided at —9— along its longitudinal center and the opposite halves are clamped together by lugs —10— and screws —11—, Fig. 2, the lugs —10— being attached to the lower and upper section of one-half section by spot welding or otherwise, and are projected across the adjacent edges of the other half section to receive the screws —11—, thereby producing a rigid case which may be made of comparatively light sheet metal to form a handle by which the device may be supported in one hand, while the other hand is employed in the operation of the strop —6—.

A stationary shaft or spindle —12— extends lengthwise of and within the lower portion of the case —1— and has its opposite ends secured in suitable openings —13— in the end walls thereof, said ends being preferably angular in cross-section to fit in corresponding openings in the ends of the case to hold the shaft against rotation and substantially co-axial with the adjacent lower wall of the case.

A hollow drum —14— having end heads —15— is rotatably mounted upon the shaft —12— within the case —1— concentric with said shaft and is provided with an interior chamber —15'— for receiving a coil spring —16— having one end secured at —17— to the shaft —12— and its other end secured at —18— to the interior of the drum for rotating said drum in a direction opposite to that imparted to it by the lengthwise movement of the strop —6—.

That is, one end of the strop —6— is wrapped one or more turns around and upon the periphery of the drum and is secured thereto, while the other end is passed over an idler drum —19— and returned downwardly through the opening —5— where it is pro-

vided with a wire loop handle —20— for drawing the strop endwise through the opening against the action of the retracting spring —16—, said drum —19— being rotatably mounted within and upon the upper portion of the casing —1— parallel with the drum —14— and concentric with the rounded upper portion of said casing.

These drums —14— and —19— are of approximately the same diameter and somewhat longer than the width of the strop —6— so as to project beyond the opposite edges of the strop, the end heads —15— of the drum —14— being provided with flanges —21— for guiding the strop against lateral displacement as it is drawn endwise in one direction by hand and returned in the opposite direction by the spring —16—, said drums being of substantially equal diameter to cause the opposite sides of the strop between the drums to travel in reverse directions in spaced relation without friction one with the other.

A pair of guide-rollers —22— are journaled within the case between and parallel with the drums —14— and —19— and at equal distances from and at opposite sides of a plane passing through the axes of said rollers slightly less than the radii of the portion of the rollers engaged by the strop so as to deflect the opposite sides of the strop between the rollers inwardly to assure the proper angle of contact of the blade in the holder —8— with the inner faces of the strop for sharpening purposes and also to hold the adjacent portions of the strop against outward displacement by the contact of the blade therewith, thereby assuring a uniform sharpening angle.

The blade-holder —8— is secured to a rock-shaft —23— to oscillate about an axis parallel with and between and in a plane extending through the axes of the drums —14— and —19— and also between said drums, and comprising a pair of opposed spring jaws —24— extending from the rock-shaft —23— toward the drum —19— and having their free ends —25— tensioned toward each other to frictionally hold the blade —a— between them, said rock-shaft —23— and blade-holder —8— being located between the drum —14— and guide-rollers —22— in such relation as to cause the cutting edge of the blade to engage the inner faces of opposite sides of the strop just above but close to the guide-rollers —22—.

A flat bow spring —26— has its opposite ends slidably interlocked with the corresponding ends of the blade-holder —8— and its intermediate portion interposed between the jaws —24— and arched toward the free edges —25— thereof to form a yielding back-rest for the back of the blade when inserted between the jaws and thereby to

assist in frictionally holding the blade in the holder during the stropping operation, the opposite jaws being flared from their free extremities toward the shaft —23— to form an intervening space for the reception of the body of the blade —a— and to enable the free edges of the jaws to more firmly engage the thinner portion of the blade a short distance back from the cutting edge thereof where it is held by the spring —26— against undue inward displacement.

The rock-shaft —23— is journaled at its ends in suitable bearings in the end walls of the case —1— and is provided at one end with a pinion segment —27— and at its opposite ends with a disk —28—, the pinion segment —27— being engaged with a gear segment —29— which is loose on the adjacent end of the stationary shaft —12—.

A friction disk or washer —30— is interposed between the gear —29— and adjacent end head —15— of the drum —14—, said gear segment being spring pressed against the washer by a coil spring —31— interposed between the outer face of the gear and adjacent end wall of the case for establishing a friction drive between the drum and gear segment, whereby motion may be transmitted to the rock-shaft —23— and blade-holder carried thereby as the drum —14— is rocked in a reverse direction by the reverse endwise movement of the strop —6—.

These toothed segments —27— and —29— are constructed to impart an oscillatory motion to the blade-holder through a limited arc of a circle approximately equal to or slightly greater than the distance between the opposite sides of the strop or just sufficient to alternately bring the opposite edges of the blade into engagement with the corresponding sides of said strop at which time, it is desired to restrain the continued movement of the blade support and this restraint is permitted by the slipping of the drum —14— relatively to the gear segment —29— as the strop continues its endwise movement in either direction after the blade has been brought into engagement with either side of the strop.

It is desirable to provide means whereby the blade-holder —8— will automatically assume a neutral position midway between the opposite sides of the strop in registration with the central part of the opening —7— in one end of the case —1— as shown in Figs. 1 and 4 and for this purpose, the end of the strop which extends through the opening —5— is provided with a metal clasp —31— which not only forms a convenient means of attachment for the handle —20— but is also provided at one end with an extension abutment —32— at the same end of the case as the disk —28— for en-

gaging an offset end —33— of a sliding plate —34— which is held in operative position by a guide-member —35— and a screw —36— and has its opposite or upper end provided with a lateral offset —37— adapted to engage a pin —38— on the disk —28— so that when the strop is retracted or drawn into the case by the action of the spring —16— and drum —14—, the abutment —32— will engage and shift the plate —34— a sufficient distance to restore the blade-holder —8— to its neutral position. For example, assuming that the parts are in their neutral or normal positions as shown in the drawings, and that it is desired to sharpen the blade of an ordinary folding razor, the latter will then be inserted endwise through the opening —6— and between the jaws —25— of the blade-holder —8— during which operation, the bow-spring will tend to force the blade outwardly between the jaws a sufficient distance to project its cutting edge beyond the free edges of said jaws, where it will be held by the spring tension of the jaws, it being understood that the blade will be wholly within the case clear from the end walls thereof.

Then by taking the case in one hand and pulling the strop outwardly by the other hand, the corresponding side of the strop will be moved in the direction indicated by arrow —X—, Figs. 3 and 4, while the opposite side of the strop between the drums will be moved in the direction indicated by arrow —Y—, thereby rotating the drum —14— in the direction indicated by arrow —M—, which through the medium of the friction disk —30— will cause the rotation of the gear segment —29— in the same direction while the pinion segment —27— will be rotated in the reverse direction indicated by arrow —N— in Fig. 3 to rock the blade-holder in the direction indicated by arrow —O— into engagement with the side of the strop opposite that to which the handle is attached or in the direction in which the edge of the blade faces to sharpen that particular side of the blade.

During this operation, the shoulder —32— on the outer end of the strop will, of course, be withdrawn from the adjacent end of the sliding plate —34—, while the pin —38— will be rocked away from the opposite end of the plate, thus leaving the sliding plate entirely free, but it is evident, however, that after the blade has engaged the strop thereby resisting further rocking movement of the blade-holder, the operator may continue to draw the strop outwardly endwise by reason of the slipping connection between the gear segment —29— and adjacent end of the drum —14— which friction is just sufficient to oscillate the blade-holder and to apply some pressure of

the blade against the side of the strop engaged thereby to increase the sharpening efficiency of the device.

On the other hand, as soon as the outward pull upon the handle —20— has been relieved, the drum —14— is immediately rotated in a reverse direction by means of the spring —16— to rewind the strop thereon during which operation, the direction of movement of the blade-holder —8— will have been reversed to bring the cutting edge of the blade into engagement with the side of the strop to which the handle is attached, which side is then moving in the direction in which the edge of the blade faces, thereby returning the pin —38— beyond its neutral position through an arc corresponding to its movement from the neutral position in the first named direction and unless the plate —34— has been returned by its own weight, it will be positively returned by the engagement of the pin —38— with the adjacent end thereof and before the engagement of the abutment —32— with the offset —33—.

As soon as, however, the shoulder —32— begins to engage the offset —33—, it will begin to return the plate —34— against the pin —38— and thereby return the blade-holder —8— to its normal or neutral position substantially midway between the opposite sides of the strop, thus completing the cycle of operation.

What I claim is:

1. In a razor stropping device, a strop support, a strop passed around the support and having opposed portions thereof extending in the same general direction therefrom and operable in one direction by hand, mechanical means for moving the strop in the opposite direction, an oscillatory blade-holder between the opposed portions of the strop, and means actuated by said mechanical means for oscillating the blade-holder first in one direction and then in the opposite direction.

2. In a razor stropping device, a strop support, a strop passed around the support and having opposed portions thereof extending in the same general direction therefrom and operable in one direction by hand, mechanical means for moving the strop in the opposite direction, an oscillatory blade-holder between the opposed portions of the strop, means actuated by said mechanical means for oscillating the blade-holder first in one direction and then in an opposite direction, and means actuated by the strop when moved in one direction for restoring the blade-holder to a neutral position substantially midway between the active sides of the strop.

3. In a razor stropping device, the combination of a case having an opening for receiving the razor blade and also provided

with an additional opening for the passage of a strop therethrough, drums mounted within the case in parallel spaced relation, a strop attached to the periphery of one of the drums and extending over the other drum and returned through the opening in the case provided therefor, an oscillatory blade-holder mounted within the case between opposed portions of the strop and normally registering with the opening for receiving the razor blade, means for rotating one of the drums in one direction for winding the strop thereon, said strop being movable by hand in the opposite direction against the action of the drum rotating means, and means actuated by the rotation of the drum in both directions for oscillating the blade-holder in reverse directions to alternately bring the blade against opposed portions of the strop.

4. In a razor-stropping device, the combination of a case having a blade-receiving-opening and a strop-receiving-opening, drums rotatably mounted within the case in parallel spaced relation, a spring within one of the drums for rotating the same in one

direction, a strop attached to the periphery of the spring actuated drum and returned over the other drum through the opening therefor, an oscillatory blade-holder mounted within the case between the drums and between opposed portions of the strop to bring the blade alternately into engagement with the opposed portions of the strop as the blade-holder is oscillated in reverse directions, said strop being moved endwise by hand in one direction to unwind it from the spring actuated drum against the action of said spring, means actuated by the rotation of the spring-actuated-drum in both directions for operating the blade-holder, and means actuated by the strop when returned to its normal position for restoring a blade-holder to a neutral position substantially midway between the opposed portions of the strop.

In witness whereof I have hereunto set my hand this 29 day of Oct. 1921.

WALTER ALTHOFF.
